UNITED STATES PATENT OFFICE

HENRY M. SCHURZ, OF CHICAGO, ILLINOIS, ASSIGNOR TO EVINRUDE MOTOR COMPANY, OF MILWAUKEE, WISCONSIN, A CORPORATION OF WISCONSIN.

DETACHABLE UNIVERSAL BRACE.

1,150,230.

Specification of Letters Patent. Patented Aug. 17, 1915.

Application filed June 7, 1915. Serial No. 32,535.

To all whom it may concern:

Be it known that I, HENRY M. SCHURZ, a citizen of the United States, residing at Chicago, county of Cook, and State of Illinois, have invented new and useful Improvements in Detachable Universal Braces, of which the following is a specification.

My invention relates to improvements in detachable universal braces for boat transoms.

The object of my invention is to provide means whereby small boats, such for example as those commonly known as row boats, may be suitably reinforced at the stern preparatory to mounting upon the transom a motor for driving the boat.

My improved apparatus is designed particularly to be employed in connection with detachable row boat motors, the braces being adapted to be transported with the motor to any point of use and attached to and detached from the boat in connection with the attachment and detachment of the motor itself.

In the drawings—Figure 1 is a fragmentary perspective view, showing the stern of a boat with a set of my improved braces applied thereto. Fig. 2 is a perspective view of one of the braces including the clamping brackets. Fig. 3 is a detail side view of one of the brackets. Fig. 4 is a detail view showing one of the brackets and a portion of a brace embodying a slightly modified form of construction.

Like parts are identified by the same reference characters throughout the several views.

A set of clamping brackets A and B are adapted respectively to engage the transom wall C and gun-wale D of an ordinary row boat. Set screws E are employed to bind the brackets to the parts with which they are connected. Each of the brackets is provided with a swiveled member F. In the construction shown these members are provided with slots to receive the flat surfaced end portions f of a brace rod G, one end of which engages the swiveled member F on bracket A and the other engages the swiveled member F on bracket B. Bolts or rivets f' connect the brace rods with the swiveled members F. The latter preferably consist of cylindrical blocks mounted on the flat upper surface of the respective brackets and secured thereto by screws H, the heads h of which

bear upon the under surface of the top of the bracket, with shanks h' of larger diameter than the screw threaded portion journaled in suitable apertures formed in the brackets.

In Fig. 4, however, I show a form of bracket A' which is provided on its upper surface with a ball receiving socket I. A ball J is seated in this socket and a brace rod G' is rigidly connected with the ball J. The brace rod G' is formed in sections connected with each other by a turn buckle K swiveled to one of the sections at k and having threaded connection with the other. It will of course be understood that the brace rod G' shown in Fig. 4 is connected at each end with the clamping bracket, the general organization of the parts being the same as that illustrated in Figs. 1 and 2. It will of course be understood that the brace rods shown in Figs. 1 and 2 may be made extensible, if desired, this feature of my invention being equally applicable to both views illustrated, said illustrations being for the purpose of description without any intention of limiting the scope of my invention to the specific form of construction shown.

It will be observed in Fig. 1 that the brace rods extend across the corners of the boat at the stern and connect an intermediate portion of the transom with a point on the gunwale a substantial distance in front of the transom. The transom is therefore supported not only by means of its direct connection with the sides of the hull and the keel, but the top of the transom is also supported from the sides of the hull by means of the diagonal braces above described. Owing to the swiveled connection between the braces and the clamping brackets, it is obvious that the braces may be connected with boats which differ in size and shape and the angle at which the brace rods extend may be varied without cramping and without interfering with the operation of clamping the brackets in position. The ball and socket joint illustrated in Fig. 4 permits a universal adjustment and additionally facilitates attaching the braces to boats in which the transom extends upwardly beyond the level of the gun-wale.

By making the clamping brackets of such form that they can be readily slipped into position upon the margin of a transom or over a gun-wale, and employing clamping

set screws to secure them in such positions, it is obvious that the braces can be quickly and easily attached and detached, and when detached they may be easily packed in a 5 suitable case containing a detachable row boat motor of the general type illustrated in Patent No. 1001260, dated August 22, 1911, issued to Ole Evinrude.

I claim—

10 1. A detachable brace for boats, including the combination with a set of clamping brackets, of a brace bar having swiveled connection at its respective ends with said brackets, said brace bar being of sufficient 15 length to support the middle portion of a row boat transom from a point on the gunwale in front of the transom, substantially as described.

2. A detachable brace for boats, including 20 the combination of a brace rod adapted to extend across the angle formed by the side and stern portion of a boat hull, a set of clamping brackets, one adapted to engage a supporting member at the side of the hull 25 and the other adapted to engage and sup-

port a member at the stern, and a connection between the brace and each of the brackets adapted to permit a swinging adjustment of the brackets with reference to the brace, substantially as described. 8

3. A detachable brace for boats, including the combination of a brace rod adapted to extend across the angle formed by the side and stern portion of a boat hull, a set of clamping brackets, one adapted to engage a 35 supporting member at the side of the hull and the other adapted to engage and support a member at the stern, and a connection between the brace and each of the brackets adapted to permit a swinging adjustment of the brackets with reference to the brace, said brace being formed in longitudinally extensible sections. 41

In testimony whereof I affix my signature in the presence of two witnesses.

HENRY M. SCHURZ.
